GIRDLE

Olga Erteszek, 7915 Haskell Ave., Van Nuys, Calif.

Filed Feb. 20, 1961, Ser. No. 64,006

Term of patent 14 years

(Cl. D20—2)

FIG. 1.

FIG. 2.

FIG. 1 is a front view of the girdle showing my new design; and

FIG. 2 is a rear view of the girdle.

I claim:

The ornamental design for a girdle, substantially as shown and described.

The characteristic features of my design reside in the combination on the girdle disclosed of the generally diamond shaped open mesh panel having a double row of stitching at the outer edges thereof and a ribbon bow and flower at the top of the panel together with feather stitching around the mesh panel, said border being relatively wide at the intermediate lower sides and merging into a relatively narrow border at the top sides of the panel, all as shown. Optional garters are depicted herein in broken lines.

I claim:

The ornamental design for a girdle, substantially as shown and described.
